TO H. W. COOPER SADDLERY HARDWARE MFG. COMPANY, OF MOLINE, ILLINOIS,
A CORPORATION OF ILLINOIS.

MOLDING-MACHINE.

1,173,414.

Specification of Letters Patent. Patented Feb. 29, 1916.

Application filed December 11, 1913. Serial No. 805,834.

To all whom it may concern:

Be it known that we, JOHN J. CREEDON and JOHN T. MILES, both citizens of the United States, and residents of Moline, in 5 the county of Rock Island and State of Illinois, have invented certain new and useful Improvements in Molding-Machines, of which the following is a specification.

This invention relates to molding machines of the squeezer type which are 10 designed to effect a compression of the flask containing the sand and pattern.

The chief object of the invention is to provide a simple, strong, convenient and 15 easily manipulated machine, and one wherein the presser-head can be readily swung away from above the molding bench or other support of the flask to facilitate the application and removal of the latter.

20 Another object of the invention is to provide a construction that will facilitate adjustment for wear of the hinge supports of the presser-head.

Still another object is to provide a construction in which the extent of throw of 25 the operating arm or lever can be readily adjusted so as to adjust the stroke of the ram according to the depths of the molding flasks.

30 Other objects and advantages of the invention will be apparent from the following description taken in connection with the accompanying drawing forming a part of this specification, in which—

35 Figure 1 is a perspective elevation, partially in vertical section of the complete device. Fig. 2 is a detail perspective elevation, partially in section, of the presser-head which carries the ram. Fig. 3 is a

40 perspective elevation of the ram detached from the presser-head. Fig. 4 is a detail elevation of the shaft which is journaled in the presser-head and operates the ram. Fig. 5 is a cross-sectional detail showing one 45 of the clutch members pinned to the operating shaft.

Referring to the drawing, 5 designates an upright beam or post on which the apparatus may conveniently be mounted.

50 6 is a molding bench strongly mounted on the post 5 by bolts 7 and constituting the support on which the flask rests during the squeezing operation. Similarly secured to the same side of the post 5 a suitable dis-

tance above the bench 6 by means of bolts 55 8 is a base-plate 9 on the outer face of which are cast a pair of integral bearing bosses or brackets 10, which are vertically apertured to receive upper and lower bearing pintles 11 and 12, respectively. The 60 lower and upper ends of the pintles 11 and 12, respectively, are tapered as shown at 11^a and 12^a; and the pintles are adjustably secured in operative position by set screws 13 and 14, respectively. 65

The presser-head consists, as here shown, of an integral casting comprising a vertical body member 15, a pair of laterally extending upper and lower arms 16 and 17, and a vertical channel-shaped casing or guide 18 70 for the stem of the ram. On the back of the channel-guide 18 is a boss 19 in which is journaled a horizontal shaft 20. The shaft 20 has formed thereon a pinion 21, that projects slightly through a transverse 75 slot 22 in the back wall of the casing-guide 18, as clearly shown in Fig. 2. This pinion 21 engages a rack 23 formed on the rear side of the vertical stem 24 of the ram. To the front of the casing 18 is secured by 80 screws 25, a removable front plate 26 constituting a guide for the front face of the plunger-stem. The upper end of the guide 18 is suitably rabbeted, as shown at 18^a to receive a cap piece 27 fitted thereon and secured in place by set screws 28. To the lower end of the ram-stem 24 is secured, as by a set screw 29, the ram-head 30; it being understood that by making the ram-head 85 separable from the stem, various sizes of 90 heads may be employed according to the character and size of the work operated upon.

The shaft 20 is removably secured in place by means of a collar 31 (Fig. 2) secured on 95 one end thereof by a set screw 32 and bearing against one side wall of the housing 18 and by means of a similar collar 33 keyed to the shaft by a through-bolt or pin 34 (Fig. 5). The outer face of the collar 33 is 100 formed with teeth 35 constituting one element of a clutch.

36 designates the operating arm or handle having a hub 37 fitted to the shaft 20; said hub having on one face teeth 38 forming the 105 other member of the clutch co-operating with the teeth 35 of the hub 33. The end of the shaft 20 carrying the arm 36 is threaded as

shown at 39, and a nut 40 carried thereby serves to force and hold the two clutch members in working engagement.

As the compression of the flask by the ram transmits a powerful upward thrust on the upper bearing spindle of the presser-head, we preferably employ a device to reinforce the holding effect of the set screw 13, such device consisting of a bracket 41 mounted upon the upper bearing bracket 10 as by a screw 42 and over-hanging the upper end of the pintle 11. Through the over-hanging end of said bracket is threaded a cap screw 43 the lower end of which bears upon the upper end of the pintle 11. Said cap screw is locked in adjusted position by a jam or lock-nut 44.

The operation of the device will be readily apparent from the foregoing description of its structure. When in idle or unused position, the presser-head may be swung to one side, thus facilitating the positioning of the flask upon the shelf 6. That done, the presser-head is swung to a position directly above the flask, the handle 36 seized and drawn forwardly and downwardly, thereby forcing the ram upon the flask under the powerful leverage afforded by the handle and the pinion and rack transmission.

30 The pivotal mounting of the presser-head by means of upper and lower hinge pintles having tapered inner ends which engage correspondingly tapered sockets in the presser-head constitutes an important feature of our invention, since it effects an automatic centering of the presser-head on the lower pintle, and, further, enables the wear occurring between the pintles and their bearing sockets to be radially taken up by a 35 simple inward adjustment of the pintles, and thus enables the true vertical position of the presser-head and ram to be maintained without the necessity of replacing a worn pintle or spindle, such as would be the case 40 where the latter extended entirely through a vertical bearing in the presser-head.

The device is easily adjusted for operation upon flasks of varying depths; this be-

ing done by backing the nut 40 off sufficiently to separate the clutch hub 37 from the clutch collar 33, raising or lowering the ram to the desired height, and then reengaging the clutch hub and collar and clamping the same by the nut 40. In this way the ram can be set the proper distance from the flask to obviate the necessity of excessive idle movement of the ram in approaching the presser-board which is commonly set on the flask before pressing.

On the arm 16 of the presser-head we 60 preferably cast a stop-lug 45 serving to limit the backward throw of the operating handle 36. The weight of the handle in such retracted position is sufficient to overcome the gravity of the ram and maintain the latter 65 in the elevated position shown when the machine is idle.

We claim—

1. In a molding machine, the combination of a relatively stationary bracket provided with vertically separated bearing lugs, a hinge pintle rotatably mounted in each of said lugs and having its end toward the other lug tapered, one of the pintles being adjustable in the direction of its length, and 75 a presser head bearing tapered sockets receiving the tapered ends of the pintles, substantially as and for the purpose described.

2. In a molding machine, the combination of a relatively stationary bracket provided with vertically separated bearing lugs, a pair of hinged pintles slidably mounted in each of said lugs and having its end toward the other lug tapered, a presser head having tapered sockets receiving the tapered ends 85 of the pintles, a member projecting laterally across the outer end of one of the pintles, and an adjusting screw mounted in said member and engaging the outer end of said pintle, substantially as and for the purpose 90 described.

JOHN J. CREEDON.
JOHN T. MILES.
